The ornamental design for a lighted charger tip for a portable electronic device, as shown and described.

DESCRIPTION

FIG. 1 is a top view of a lighted charger tip for a portable electronic device showing my new design;

FIG. 2 is a bottom view of the lighted charger tip for a portable electronic device of FIG. 1;

FIG. 3 is a front view of the lighted charger tip for a portable electronic device of FIG. 1;

FIG. 4 is a rear view of the lighted charger tip for a portable electronic device of FIG. 1;

FIG. 5 is a right view of the lighted charger tip for a portable electronic device of FIG. 1;

FIG. 6 is a left view of the lighted charger tip for a portable electronic device of FIG. 1; and,

FIG. 7 is a perspective view of the lighted charger tip for a portable electronic device of FIG. 1.

The broken lines shown depict portions of the lighted charger tip for a portable electronic device that form no part of the claimed design.
